UNITED STATES PATENT OFFICE

134,348

DESIGN FOR A COMBINED HOE AND RAKE HEAD

Harry M. Thayer, Woodhull, Ill., assignor of one-eighth to Gertrude S. Gamel, Alpha, Ill.

Application July 29, 1942, Serial No. 107,733

Term of patent 14 years

To all whom it may concern:

Be it known that I, Harry M. Thayer, a citizen of the United States, residing at Woodhull, in the county of Henry and State of Illinois, have invented a new, original, and ornamental Design for a Combined Hoe and Rake Head, of which the following is a specification, reference being had to the accompanying drawing, forming part thereof.

Figure 1 is a side elevational view of a combined hoe and rake head, showing my new design.

Figure 2 is a top plan view, and

Figure 3 is an end elevational view.

I claim:

The ornamental design for a combined hoe and rake head, as shown.

HARRY M. THAYER.
